225,660

TOY SHOVEL LOADER

Yasuta Satoh, 758, 5-chome, Matsugaoka,
Nagareyama, Japan

Filed Mar. 15, 1971, Ser. No. 124,629

Claims priority, application Japan Jan. 30, 1971

Term of patent 14 years

Int. Cl. D21—01

U.S. Cl. D34—15

FIG. 2

FIG. 3

FIG. 1

FIG.4

FIG. 5

FIG. 6

FIG. 1 is a front elevational view of a toy shovel loader;

FIG. 2 is a top plan view;

FIG. 3 is a bottom plan view;

FIG. 4 is a side elevational view as seen from the right side of FIG. 1, the upper portion being shown fragmentarily for convenience of illustration;

FIG. 5 is a side elevational view as seen from the left side of FIG. 1; and

FIG. 6 is a back elevational view.

I claim:

The design for a toy shovel loader, substantially as shown and described.
